RAZOR BLADE SHARPENER

Adolf Liermann, Philadelphia, Pa.

Application November 19, 1932, Serial No. 643,334

3 Claims. (Cl. 51—161)

This invention relates to devices for sharpening razor blades, particularly safety razor blades.

My invention has for its main object the provision of simple and inexpensive devices of the kind referred to whereby safety razor blades of various standard types can be sharpened quickly and effectively for re-use.

The indicated advantages I realize, as herein-after fully disclosed, in a sharpening device consisting of two parts or components, one a sharpening member with a hollow affording a smooth hard rounded sharpening surface, and the other a rotary holder for the blades fitting the hollow of the first mentioned component and affording a resilient seat whereby the blades are gently pressed so that their sharpening edges are maintained in light contact with the curved inner surface of the sharpening member.

Other objects and attendant advantages of this invention will be manifest from the following detailed description of the accompanying drawing; wherein, Fig. I is a perspective view of my improved razor blade sharpener showing how the same is used.

Fig. II is a perspective view of the blade holder component of the device showing a double-edged safety razor blade in place thereon.

Fig. III is an end elevation of the blade holder looking from the left of Fig. II.

Fig. IV is a fragmentary sectional view taken as indicated by the arrows IV—IV in Fig. I.

Fig. V is a perspective view of a resilient seating pad whereby the blades are yieldingly supported on the holder.

Figs. VI and VII are views corresponding to Figs. II and III showing a safety razor blade with a single cutting edge in place on the holder.

As delineated in Fig. I of these illustrations, the razor blade sharpener of my invention comprises a sharpening member 10, and a blade holder 11. The sharpening member 10, it will be noted, is hollow, and, in the present instance, has the form of a drinking glass or tumbler which is preferably made of glass and whereof the interior is slightly tapered inwardly with provision of a hard smooth and somewhat conical round sharpening surface 12. The blade holder 11, on the other hand, is preferably fashioned from wood or molded from a suitable composition such as "bake-lite" for example, with the body portion 13 which is tapered and rounded to fit the hollow of the sharpening member 10, and formed at one end with a finger grasp 14, which, when the parts are assembled as in Fig. I, projects diametrically beyond the mouth of said sharpening member,

From Figs. III and IV it will be observed that the blade holder 11 has a transverse profile corresponding to that of a bell. The rounded bottom surface 15 of the blade holder 11 provides a substantial conformative area to firmly bear on the inside of the surface 12 of the sharpening member 10, and a narrower curved top surface 16 of smaller radius on which is mounted a resilient pad 17 (Fig. V) of soft rubber or the like that serves as a retaining seat for the razor blades. 65 As shown, the pad 17 is formed with three longitudinally-arranged upstanding circular projections 18 which are spaced to fit the hollows (or lateral indentations of longitudinal slots as the case may be) of standard double-edged safety 70 razor blades like the one indicated at B in Figs. I and II to centralize and prevent displacement of such blade on the holder 11 during the sharpening operation. A packing 19 of absorbent material like felt is lodged in a longitudinal 75 medial groove 20 in the rounded bottom surface 15 of the holder 11 to serve as a medium for holding a quantity of water or other suitable lubricating medium.

In using the device the double-edged razor 80 blade B is placed on the resilient pad 17 of the holder 11 with its openings engaging the projections 18 of said pad after the manner illustrated in Figs. I—III. The holder 11 is then inserted into the hollow of the sharpening member 10 as 85 in Fig. I incident to which the resilient pad 17 yields to permit slight flexure of the razor blade B so that the upper bevels of the cutting edges of said blade lay tangentially against the curved sharpening surface 12 of the member 10 as shown 90 in Fig. IV. With the parts so positioned the holder 11 is oscillated or rotated with the result that the contacting bevels of the blade edges are rubbed back and forth over the sharpening surface of the member 12. After several oscillations or rotations of the holder 11, the latter is removed, the blade B inverted, and the operation repeated as before. During the sharpening operation, lubricant is supplied to the surface 12 of the sharpening member 10 by the wetted packing 19 at the bottom of the blade holder 11. Obviously, the pressure on the blade edges may be increased by forcing the holder 11 further into the tapered hollow of the sharpening member 10 to insure proper tangency as between the 100 bevels of the blade edges and the sharpening surface 12.

My sharpener may also be used to sharpen single edged blades such as the one indicated at B' in Figs. VI and VII, which blade is placed on 110

the resilient pad 17 so that its reinforcing strip R abuts the projections 18 of said pad as shown. The blade B' is thus definitely positioned on the holder 11 and when the latter is inserted in the hollow of the sharpening member 10, said blade is prevented from shifting under the pressure exerted by the resilient pad 17. After several rotations or oscillations, the blade holder 11 is removed from the member 10, the blade B' reversed, and the operation repeated in exactly the same manner as hereinbefore described in connection with the sharpening of double-edged blades.

Having thus described my invention, I claim:

- 15 1. A razor blade sharpening device comprising a sharpening member with a hollow affording a smooth hard rounded sharpening surface; and a rotary blade holder fitting the hollow of the sharpening member, said holder being adapted to support a razor blade with its cutting edge in light rubbing contact with the rounded surface of the sharpening member, and carrying a wetted material to lubricate the sharpening surface aforementioned incident to oscillation or rotation of the holder.
- 25 2. In a device of the type described the combination of a member having an inner smooth

and hard cylindric sharpening surface, and a rigid material rotary blade holder fitting into the inner cylindric surface, said holder embodying an end finger-hold and being of bell-like transverse profile to provide a longitudinal base conformative to the sharpening surface with a diametrically opposing narrower surface of smaller radius, a retaining seat of resilient material in the narrower surface with projections to engage the customary apertures in a conventional safety-razor-blade, and an inset pad of absorbent material medially coextensive of the longitudinal base to hold suitable lubricating medium.

3. As an article of manufacture a safety-razor blade holder comprising a rigid material block embodying a finger-hold extension at one end and being of bell-like transverse profile to provide opposing longitudinal curved surfaces of different width and radius, the wider of said surfaces having an inset pad of absorbent material medially coextensive thereof, and the narrower surface including an attached strip of soft resilient material embodying spaced projections to hold a conventional safety-razor blade.

ADOLF LIERMANN.
